UNITED STATES PATENT OFFICE.

HENRY M. CRANE, OF NEW YORK, N. Y., ASSIGNOR TO WESTERN ELECTRIC COMPANY, OF CHICAGO, ILLINOIS, A CORPORATION OF ILLINOIS.

ELECTROMAGNETIC SIGNAL-CONTROLLING DEVICE.

No. 890,220.

Specification of Letters Patent.

Patented June 9, 1908.

Application filed January 29, 1906. Serial No. 298,317.

To all whom it may concern:

Be it known that I, HENRY M. CRANE, citizen of the United States, residing at New York, in the county of New York and State 5 of New York, have invented a certain new and useful Improvement in Electromagnetic Signal-Controlling Devices, of which the following is a full, clear, concise, and exact description.

10 My invention relates to an electromagnetic signal controlling device, and has for its object to provide an improved, simplified and efficient magnetic controller adapted to effect the sequential operation of electrical 15 devices or mechanisms.

The device of my invention is capable of specially advantageous use in connection with telephone exchange service, being adapted for use as a combined line and cut-off relay.

Generally speaking, my invention contemplates a magnetic controlling device comprising an electromagnet provided with two armatures, one of which is adapted when attracted to operate a contact device and close a gap in the magnetic circuit of said magnet, said armature being responsive to current in said magnet. The other armature is adapted to respond upon the closure of said magnetic gap by said first-mentioned armature to an increase of current through said magnet, and is arranged when attracted to operate contact devices associated therewith. With my device, therefore, employing but a single magnet, a sequential operation of circuit controlling devices may be obtained.

I will describe my invention by reference to the accompanying drawing, wherein,

Figure 1 is a side elevation of an electromagnetic signal controlling device embodying my invention; Fig. 2 is an end view thereof; Fig. 3 is a plan view; Fig. 4 is a longitudinal sectional view on line 4-4 of Fig. 3; and Fig. 5 is a detail view of the end 45 of the magnet, with the armature removed, showing the contact made thereby.

The same letters of reference are used to designate the same parts wherever shown.

Referring now to the drawing, which shows 50 the preferred form of my invention, the magnet *a* of the controlling device is provided

with a core *a'* surrounded by a pair of magnet windings or helices *a²* *a²*. A light armature *b*, preferably L-shaped, is mounted adjacent to one end *a³* of the magnet core, and adapted when attracted to engage said core and thereby close a gap in the magnetic circuit of the magnet *a*. Said armature is arranged to be responsive to current in one of the windings *a²* and controls a pair of contacts *c* *c'*, which may serve, when my device is used in telephone exchange work, as the line relay contacts.

An armature *d* is provided for the magnet, preferably movably secured to an L-shaped extension *e* of the end *a⁴* of core *a'*, so as to lie parallel to the magnet spool, with its free end extending adjacent to one arm *b'* of armature *b*, said arm preferably lying above the armature *d* and in approximately the same plane therewith. The armature *d* is preferably connected to the extension *e* by means of a flexible member *h*, said member serving to permit the movement of the armature *d*. The armature *d* also controls a gap in the magnetic circuit of said magnet, and is adapted to respond when the magnetic gap controlled by armature *b* is closed, to current flowing in order of said windings *a²*. The armature *d* when attracted engages the arm *b'* of armature *b*, closing the magnetic gap controlled thereby and completing the magnetic circuit of said magnet. The armature *d* is thus primarily under the control of armature *b*, and after the armature *b* has acted to close the gap, the control of armature *d* is transferred to its magnet winding, which upon receiving current, increases the magnetic flux to effect the operation of said armature. It will be noted that the armatures *b* *d* are serially included in the magnetic circuit of the electromagnet, each of said armatures forming a return pole piece for the other.

The armature *d* is adapted in its movement 95 to operate contact devices *f*, which in the present instance comprise three contact springs and their anvils, mounted upon but insulated from the core extension *e*, the armature preferably carrying pins *g* adapted upon 100 the movement of said armature to engage and separate said springs from their anvils.

These contact springs in telephone service might control the line and line signal circuits, in the manner of the well known cut-off relay.

I claim:

5. 1. The combination with a magnet having two gaps in its magnetic circuit, of an armature for said magnet responsive to current therein while both gaps are open, said armature being adapted in its attractive movement to 10 close one of said gaps, and a second armature for said magnet unresponsive while both gaps are open to the current operating said other armature, said second armature being adapted to respond, upon the closure of said gap by 15 said first mentioned armature to an increase of current in said magnet and to close said other gap. 70
2. The combination with a magnet having two gaps in its magnetic circuit, of an armature for said magnet responsive to current therein adapted to close one of said gaps, and a second armature for said magnet, responsive upon the closure of said gap, to an increase of current in said magnet, the closure 25 of said second gap being effected jointly by 80 said armatures. 85
3. The combination with an electromagnet having two windings, of two armatures included in the magnetic circuit of the magnet, said circuit having an air gap between 30 the core of the magnet and one of said armatures, and a second air gap between said armatures, one of said armatures being arranged to respond while both of said gaps are open 35 to a current in one of the windings of said magnet to close said first mentioned gap, and said other armature being arranged to respond to an increase in the magnetic flux in 40 said circuit produced by the closure of said first mentioned gap and the current in both 90 said windings. 95
4. The combination with an electromagnet having two windings, of two armatures pivoted to swing in planes perpendicular to 45 each other and included in the magnetic circuit of said magnet, said circuit having two air gaps therein, one of said armatures being responsive to current in one of said windings to close one of said gaps, and said other armature being responsive to the increased magnetic flux due to the closure of said gap and to current in both of said windings to close 50 said other gap. 100
5. In an electric signal controlling device, 55 the combination with an electromagnet, of an armature for said magnet responsive to current therein, said armature when attracted closing a gap in the magnetic circuit of said magnet, a second armature for said 60 magnet also controlling a gap in the magnetic circuit, the free end of said armature lying adjacent said first mentioned armature, said second armature being adapted to respond upon the closure of said first mentioned magnet to an increase of current in said 65 magnet, thereupon engaging said first mentioned armature to close the second magnetic gap and complete the magnetic circuit of the magnet, and mechanism controlled by 70 said armatures. 75
6. In an electric signal-controlling device, the combination with an electromagnet, of an L-shaped armature for said magnet responsive to current therein, one arm of said armature lying parallel to the magnet spool, 80 said armature when attracted closing a gap in the magnetic circuit of said magnet, a second armature lying parallel to the magnet spool and controlling a gap in said magnetic circuit, the free end of said armature lying 85 close to said arm of the L-shaped armature, said second armature being adapted to respond upon the closure of the gap controlled by the first mentioned armature, to an increase of current in said magnet, thereupon 90 engaging said arm of the L-shaped armature to close the second magnetic gap and complete the magnetic circuit of said magnet, and mechanism controlled by said armatures. 95
7. The combination with a magnet having two gaps in its magnetic circuit, of an armature for said magnet adapted to close one of said gaps and partially close the other gap, and a second armature for said magnet responsive upon the closure of said first mentioned gap to current in said magnet to effect 100 the complete closure of said other gap. 105
8. The combination with the magnet core, of two armatures movably mounted to form, with each other and with said core, a complete magnetic circuit, said circuit being closed by said armatures in their attracted positions. 110
9. The combination with a single spool electromagnet, of a core for said magnet, and two armatures adapted to jointly complete a magnetic circuit for said core, said armatures being serially included in said magnetic circuit. 115
10. The combination with a single spool electromagnet, of two armatures for said magnet, each of said armatures forming the return pole piece for the other. 120
11. The combination with an electromagnet, of two armatures therefor adapted when attracted to engage each other to complete the magnetic circuit of said magnet. 125
12. The combination with an electromagnet, of two armatures therefor adapted to form magnetic extensions from opposite ends of the magnet core, the free ends of said armatures being adapted to engage to complete the magnetic circuit of said magnet. 130
13. The combination with an electromagnet, of an L-shaped armature mounted before one end of the magnet core, an L-shaped magnetic extension from the other end of said core, an armature supported by 135

890,220

3

said extension, said armatures when both attracted engaging to complete the magnetic circuit of said magnet.

14. The combination with an electro-magnet, of an armature therefor, contacts controlled by said armature, a second armature for said magnet lying parallel thereto, said armatures when both attracted completing the magnetic circuit of said magnet, 10 and contact springs lying parallel to said

second armature and operated by said armature in its movement.

In witness whereof, I hereunto subscribe my name this twenty fourth day of January A. D., 1906.

HENRY M. CRANE.
